CABINET

Irvine H. Bouchard, Radio Distributing Co.,
1212 High St., South Bend, Ind.

Filed Jan. 8, 1958, Ser. No. 49,168

Term of patent 14 years

(Cl. D33—19)

FIG. 1

FIG. 2

I claim:

The ornamental design for a cabinet, substantially as shown.
